UNITED STATES PATENT OFFICE.

DENNIS C. O'SHEA, OF CHICAGO, ILLINOIS.

GARMENT.

1,255,560.

Specification of Letters Patent.

Patented Feb. 5, 1918.

Application filed May 29, 1917. Serial No. 171,660.

To all whom it may concern:

Be it known that I, DENNIS C. O'SHEA, a citizen of the United States, residing at Chicago, in the county of Cook and State of Illinois, have invented a new and useful Improvement in Garments, of which the following is a specification.

My invention relates to certain new and useful improvements in garments and is 10 fully described and explained in the specification and shown in the accompanying drawings, in which:

Figure 1 is a perspective view of my improved garment and Fig. 2 is a section on 15 the line 2 of Fig. 1.

Referring to the drawings, my garment will be seen to be in the form of an ordinary coat or reefer, the back 3 and sides 4 being of a suitable closely woven fabric. Materials 20 of this character, and of the requisite warmth for use in cold weather, are exceedingly stiff and make it difficult for the wearer to perform such exercises as are frequently desired. Garments of such cloth are 25 peculiarly binding to the arms and constricting to the chest, interfering seriously with the free play of the arms and shoulders. In my garment, therefore, the sleeves 30 5 are made of knitted material, preferably double. Furthermore, the front of the coat, which is made double-breasted, is finished with a wide margin of double knitted sweater material 6 which is continued upward to form a collar 7 of the well-known 35 shawl type. This garment affords to the wearer several advantages. The arm action

is practically as free as in a knitted garment, and the knitted front part affords a measure of elasticity which permits the shoulders to be freely moved without drawing across the chest and body. Furthermore, the elasticity and softness of the fabric furnishes a collar which clings to the neck and is much more comfortable than if it were made of woven material. At the 45 same time the warmth and imperviousness of a heavy woven fabric are in the main preserved so that the maximum of warmth is preserved so far as it is compatible with the necessary flexibility.

I realize that considerable variation is possible in the details of this construction without departing from the spirit of my invention; therefore I do not intend to limit myself to the specific form herein shown and described except as pointed out in the following claim, in which it is my intention to claim all the novelty inherent in the construction as broadly as is permitted by the state of the art.

What I claim as new and desire to secure by Letters Patent is:

The herein-described garment having a body portion of heavy woven fabric, knitted relatively flexible long sleeves, and a knitted 65 relatively flexible front part, said front part being carried upward and around the neck to form a knitted shawl collar.

In testimony whereof I have hereunto set my hand this 5th day of May, 1917.

DENNIS C. O'SHEA.
